OF NEW YORK, N. Y.

INDEX FILE MOUNTING

Application filed September 1, 1927. Serial No. 216,897.

This invention relates to a mounting for filing devices and more particularly to a mounting for visible index files in which the files are relatively movable so that they may be positioned for convenient access to the indexes or into a position when not in use in which they will occupy a minimum amount of space.

An object of the invention resides in providing a mounting structure for a plurality of index files which may be readily moved about an office and support the files for relative movement to present the same for ready access to the indexes therein.

10 A further object of the invention resides in providing a file mounting in which file supporting members or trays are movably supported in a horizontal position in a suitable stand so that the files carried thereby 15 may be manually moved into a convenient position to provide access to the indexes of all of the files while they may also be moved into such relation when not in use that they will be housed within the supporting frame 20 and occupy a minimum of floor space.

Another object of the invention resides in providing a mounting for filing devices in which a stand provided with suitable end members mounts a plurality of pairs of arms 30 pivotally mounted to the end members of the stand and carrying file supporting members and their free ends for relative movement in horizontal relation so that a plurality of files may be stored in a minimum of floor space 35 and yet be readily movable into accessible positions to permit the use of the files for indexing or filing purposes.

This invention further comprehends numerous improvements in the details of construction of the parts to secure efficient operation thereof and simplicity in assembly which are all more particularly pointed out in the following detailed description and in the claims, directed to a preferred form of the invention, it being understood however, that various changes in the size, shape or relation of these elements may be made without departing from the spirit or scope of the invention as herein set forth.

In the drawings forming part of this application,

Fig. 1 is a side elevation of the improved index file mounting device;

Fig. 2 is an end elevation of a file mount- 55 ing showing the files in position;

Fig. 3 is a diagrammatic illustration showing the arms and file supporting members in one position in full lines and other positions thereof in dotted lines, and dot and dash lines;

Fig. 4 is a detailed sectional view taken on line 4—4 of Fig. 2 and illustrating particularly a means for insuring uniform movement of all the arms and one of the latch 65 means for retaining the arms in adjusted position; and

Fig. 5 is a detailed sectional view taken on lines 5—5 of Fig. 4.

A stand is indicated generally at 1 which 70 includes a pair of end members each comprising an inverted U-shaped rod or pipe members 2 having the lower free ends joined by bar members 3. The free ends of these U-shaped members receive and mount suitable 75 casters or the like indicated at 4 so that the stand may be readily moved over a floor or other supporting surface. The end members are rigidly secured in spaced parallel relation through the medium of bar members 5 80 secured to the lower ends of the inverted U-shaped members 2 as clearly shown in Figs. 1 and 2. In the upper portion of these U-shaped members 2 are secured suitable bearing brackets 6 having a cross bar 7 extending 85 between the opposite sides of the members in which is formed a guide bearing or arcuate slotted portion 8. From the central portion of this arcuate portion 8 an extension 9 projects upwardly and is detachably secured to the upper 90 central portion of the member 2 as clearly shown in Fig. 2. The central portion of the cross bar 7 of each bearing bracket and the end portions thereof are provided with bearings indicated at 10 for rotatably mount- 95 ing a plurality of pairs of supporting arms 11 and 12. The pairs of supporting arms 11 are rotatably mounted adjacent their central portions in the bearings at the ends of the cross bar 7 while the pair of supporting arms 100

12 are rotatably supported in the central bearings in the cross bar 7. The free ends of these pairs of arms 11 and 12, which are all of equal length, are provided with suitable journals in which are rotatably mounted the stub shafts 13 carried by the lateral projections 14 on the bottom of the file supporting members or trays 15.

The central pair of supporting arms 12 are rigidly connected by the bar member 16 above the pivotal mounting 10 on the cross bar, the ends of this rod 16 extending through and beyond the arms as shown in Fig. 4 and having guide rollers 17 suitably mounted on the reduced extensions for rotation thereon and movement in the arcuate slots in the arcuate portion 8 of the bearing brackets. This guide construction also limits the rotation of the arms 11 and 12 on their respective bearings in the bearing brackets. The outer face of each of the arms 12 is formed with a projection 18 slotted as indicated at 19, while the bearing brackets mount a plurality of latch members 20 adapted to engage in the slot 19 as shown in Figs. 4 and 5 to retain the supporting arms in desired positions of adjustment. The latch member 20 is slidably projected from a recess 21 in the bearing bracket by a suitable coil spring 22 and is limited in its movement by the knob 23 mounted on the reduced extension 24 extending through the bearing bracket and carrying the knob 23 on the outer end thereof as clearly illustrated in Fig. 4. The knob 23 may be manually engaged for releasing the latch member 20 from the slot 19 by pulling the same outwardly so that the latch member compresses a spring in the recess 21.

The ends of the arms 11 and 12 as shown in Fig. 2 at opposite sides of the central pivot 40 are of unequal length, the lower ends being longer so that one supporting member and its carried file will always gravitate to the bottom portion of the stand. A sufficient number of latch members are employed to retain 45 the arms in the various positions necessary for convenient use of the files as illustrated in Fig. 3.

Index files are indicated at 25 which may be of any suitable type well known and now 50 used in the art, which are mounted on the file-supporting members 15 recessed in the upper face as indicated at 26 in dotted lines to receive the lower edge portion of the files 55 so that they will be held in place on the supporting members.

With a construction of this character it will be seen by reference to Fig. 3 that the files carried by the supporting members 15 may be moved into a plurality of relative positions in which the file supporting members are always maintained in horizontal relation. In Fig. 3 the files are illustrated in one position in full lines so as to provide access to each of the files on the supporting members 65 for filing purposes. Should it be desired to

reverse the position of these files with respect to one another, the same may be manually moved so as to rotate the supporting arms in the direction of the arrow 26 in Fig. 3 until these files assume the dotted line position indicated at 27. When the files are not in use it is usually desired to store the same in such a manner that they will require the least amount of floor space and for which purpose the files will move by gravity into the position shown by the dot and dash lines at 28 in Fig. 3 through the rotation of the supporting arms so that all of the files are within the plane of the stand 1.

This invention therefore provides a mounting for index files in which the supporting members are freely movable to position the files in any desired relation for storage or access to the contents in any of which positions the latching means will retain the files through cooperation with the supporting arms, while at the same time an even and free movement of the supporting members will be obtained through the operation of the guiding means carried by the arms 12.

What is claimed is:

1. An index file mounting, comprising a stand having rigidly connected end members, file-supporting members, a plurality of pairs of supporting arms pivotally mounted on said end members and having corresponding ends connected to the same supporting member for mounting said supporting members movable relative to the stand in substantially horizontal relation, and a guide rod connecting one pair of arms and having the free ends guided in slots formed in said end members.

2. An index file mounting, comprising a stand having end members and means connecting said end members at their lower ends, a guide bearing on each of said end members, file supporting members, a plurality of pairs of arms pivotally mounted intermediate their ends on said end members and having corresponding ends pivoted to the same file supporting member for movably supporting said supporting members in parallel relation, means connecting one pair of said arms at a spaced distance from said pivotal mounting on said end members, said means engaging with said guide bearings of said end members to permit supported movement of said connected pair of arms.

3. An index file mounting comprising a stand having spaced end members, a bearing bracket on each of said end members, said bearing bracket having a guide bearing and spaced latch members, a plurality of pairs of arms pivotally mounted intermediate their ends on said end members, a pair of file supporting members, each file supporting member being pivotally connected to all of the arms at each extremity thereof, means

connecting one pair of said arms at a spaced distance from said pivotal mounting on said end members, said means engaging with said guide bearings of said end members for limited movement therein, latch engaging means on said connected pair of arms adapted to selectively engage either of said latches on said bearing bracket when said means reaches its limit of movement in said guide bearings.

4. An index file mounting comprising a stand having a pair of end members including inverted U-shaped sections and means securing the free ends of said sections; a bearing bracket within each section, said bearing bracket having an extension secured to the top central portion of said section, a pair of oppositely extending arms each connecting to opposite sides of the section, and a bearing in said bracket at the juxtaposition of said arms and extension; means securing the end members in spaced relation and file supporting means extending between said end members and mounted in said bearings thereof.
